**SINGLE MAGNETIC CARD-CONSOLE UNIT FOR
AN ELECTRONIC TYPING SYSTEM**

Robert A. Clowe, Penfield, N.Y., assignor to
Xerox Corporation, Stamford, Conn.

Filed Nov. 22, 1974, Ser. No. 526,296

Term of patent 14 years

Int. Cl. D14—02

U.S. Cl. D26—5 C

FIG. 1

FIG. 2

FIG. 3

FIG. 4

FIG. 5

FIG. 6

FIG. 1 is a right front perspective view of a single magnetic card-console unit for an electronic typing system showing my new design;

FIG. 2 is a front elevational view thereof;

FIG. 3 is a rear elevational view thereof;

FIG. 4 is a top plan view thereof;

FIG. 5 is a left side elevational view thereof; and

FIG. 6 is a right side elevational view thereof.

I claim:

The ornamental design for a single magnetic card-console unit for an electronic typing system, as shown.
